UNITED STATES PATENT OFFICE

ROBERT F. TRACHT, OF GALION, OHIO, ASSIGNOR TO THE CENTRAL OHIO STEEL
PRODUCTS COMPANY, OF GALION, OHIO, A CORPORATION OF OHIO

DESIGN FOR A BURIAL VAULT

Application filed February 28, 1933. Serial No. 47,354. Term of patent 7 years.

To all whom it may concern:

Be it known that I, ROBERT F. TRACHT, a citizen of the United States, residing at Galion, in the county of Crawford and State of Ohio, have invented a new, original, and ornamental Design for a Burial Vault, of which the following is a specification, reference being had to the accompanying drawing, forming part thereof.

Figure 1 is a perspective view of the burial vault showing my new design;

Figure 2 is a sectional view through one side of the vault on the line 2—2 of Figure 1.

I claim:

The ornamental design for a burial vault, as shown.

ROBT. F. TRACHT.
